UNITED STATES PATENT OFFICE

JAMES B. EVANS, OF SPRINGFIELD, MISSOURI.

DESIGN FOR A BUTTON OR BADGE.

SPECIFICATION forming part of Design No. 24,629, dated August 27, 1895.

Application filed July 1, 1895. Serial No. 554,649. Term of patent 3½ years.

To all whom it may concern:

Be it known that I, JAMES B. EVANS, a citizen of the United States, residing at Springfield, in the county of Greene and State of Missouri, have invented and produced a new and original Design for a Button or Badge, of which the following is a specification, reference being had to the accompanying drawing, showing a part thereof.

10 The accompanying drawing represents a top plan view of the head of a button or badge embodying my design.

My design consists, essentially, of a circular-shaped button or badge composed of two 15 semicircular divisions of contrasting colors and having upon the face of the button or badge the representation of two American flags, with their staffs arranged in the form of a V, the angle formed by this arrangement 20 of the staffs being at or near the circumference of the head of the button, and being approximately bisected by the line of division between the two contrasting portions, so that one flag will be on either side, and these two

flagstaffs are connected by a short chain, as 25 shown in the accompanying drawing.

In the drawing, A and B represent the two semicircular divisions of the face of the button or badge, of contrasting colors.

A' and B' represent the two flags, having 30 staffs a and b, respectively, meeting each other at a b, and C represents the chain connecting these staffs.

X indicates the line of division between the two semicircular portions of the face of the 35 button.

The figures of the flags and chain may or may not be raised, as desired.

What I claim as my invention is—

The design for a button or badge, made 40 substantially as herein shown and described.

In testimony whereof I affix my signature in presence of two witnesses.

JAMES B. EVANS.
